UNITED STATES PATENT OFFICE.

EDWIN W. M. BAILEY, OF AMESBURY, MASSACHUSETTS.

WINDOW-GLASS GUIDE.

Application filed June 9, 1926. Serial No. 114,711.

This invention relates to means for guiding vertically sliding sheets of window glass employed in automobile bodies of the closed type, and, more particularly to a type of guide illustrated in my prior Patent No. 1,521,168, which comprises a strip of resilient metal shaped in channel form and lined with felt, or like cushioning material.

Guides of these types are used in connection with various door and frame constructions, with many of which much difficulty is encountered in replacing broken glass, as the guide must usually be extended for some distance, a foot or more, below the level of the window rail at the lower end of the opening, and, while the portion of the guide above this point may be usually removed, or displaced by removing a molding strip at one side of the guide, access to the portion of the guide beneath the window opening is usually difficult, so that the labor expense incident to replacing the glass has often been greater than the cost of the glass alone. On account of this difficulty, and because of the fact that a metal channel strip, such as above referred to, cannot be bent without serious detriment thereto, I have adopted the expedient of making each guide in two sections which terminate at adjacent ends a short distance below the lower end of the window opening, so that the moldings at the sides of the upper sections and the sill may be removed, permitting the upper sections also to be removed, so that they may be placed on the edges of the glass and then the glass may be placed in the opening and slid down into the guide sections below the opening. This arrangement has been found to be objectionable, by reason of the tendency of the felt lining to be displaced or pressed into bunches at the top end of the lower section, so as to obstruct the guideway, and the primary object of my present invention is to provide a form of felt lined spring metal channel which will enable the window glass to be replaced in the manner above indicated and which will avoid the difficulty of having the felt lining displaced when the glass is inserted in the lower section, or is slid downward therein.

I accomplish these objects in the manner hereinafter described and illustrated in the accompanying drawing in which:

Fig. 1 is a side view of a window glass guide embodying my invention.

Fig. 2 is a front elevation thereof partly

in section showing the guide in position to permit insertion of the glass sheet.

Fig. 3 is a similar view of a portion of the guide, in normal position.

Fig. 4 is a transverse sectional view and

Fig. 5 is a detail perspective view of a portion of the guide in the position of Fig. 2.

In the drawings a window casing 1 is indicated, having removable molding strips 2, at each side of the window opening, which extend from the top to the bottom of the opening and form grooves for the reception of the metal channel strip 3, which is lined with a felt cushioning strip 4, as disclosed in said prior patent.

According to my invention I form the metal channel strip 3, at each side of the window opening, in two sections, viz an upper section 3^a, which extends from the upper end of the opening to a point a short distance below the lower end of the opening, and a lower section 3^b, which abuts at its upper end with the lower end of the upper section 3^a, and extends to the lowest point to which the window glass 5 is moved when it is lowered to its fullest extent.

The felt lining strip 4 is extended continuously from the upper end of the upper section to the lower end of the lower section, so that it extends across the joint between the metal section and makes the interior portion of the guide, which directly engages the glass, continuous.

In replacing the glass sheet, the molding strips 2 are removed, permitting the upper sections 3^a to be swung out at their upper ends from the position in which they were held thereby, as indicated in Figs. 2 and 5, the felt strip 4 acting as a flexible connection between the sections, and permitting such movement so that, when the glass is to be inserted, its lower edge portions at each side will be passed into the upper ends of the upper sections and slid down therein, to the lower end thereof, then the glass, with the guides thereon may be swung into position in the opening, so that the upper sections will be carried into alignment with the lower sections and into the position in which they may be secured by the molding. In this position the glass may then be slid down into the lower sections and, as the lining of the sections is continuous, there will be no tendency to cause obstruction of the glass, by the engagement of its lower edge with

the felt at the upper end of the lower sections, so as to dislodge it and press it down in a manner to fill or partly fill the groove in which the glass is arranged to slide.

5 I claim:

In a casing having a window opening, and a vertically slidable window glass sheet, for closing said opening, adapted to be lowered to open the same, a pair of vertically disposed guides for the side edge portions of the sheet, each guide comprising two normally aligned channel metal strip sections arranged with their adjacent ends in abut-

ment with the lower section terminating at its upper end adjacent the bottom of the 15 opening and a flexible cushioning lining secured within said strip sections and extending continuously from one section to the other to provide guiding surfaces between said sections, said lining being adapted to 20 permit the upper section to be swung out of line with the lower section so that the sheet may be inserted at the upper end thereof.

In testimony whereof, I have signed my name to this specification.

EDWIN W. M. BAILEY.
